PRESS-GUARD.

1,274,612.

Specification of Letters Patent. Patented Aug. 6, 1918.

Application filed August 23, 1916. Serial No. 116,424.

To all whom it may concern:

Be it known that I, GEORGE H. SEARS, of Rochester, in the county of Monroe and State of New York, have invented certain 5 new and useful Improvements in Press Guards; and I do hereby declare the following to be a full, clear, and exact description of the same, reference being had to the accompanying drawings, forming a part of 10 this specification, and to the reference-numerals marked thereon.

My present invention relates to machinery and more particularly to punch presses and similar machines that are intermittently operated under the control of a workman in which there is danger of injury to the latter's hands due to the insertion or removal of the workpieces acted upon by the ram or dangerous element of the machine, and it has 20 for its object to provide an automatic guard for ejecting the arm or hand from the dangerous region and blocking its entrance thereto, which guard will be of cheap and simple construction and convenient and efficient in its operation. The invention is directed in part toward making the guard mechanism accessible and also readily displaceable for purposes of adjustment and also to allow the occasional operation of the 25 press independently of the safety devices. To these and other ends the invention resides in certain improvements and combinations of parts all as will be hereinafter more fully described, the novel features being 30 pointed out in the claims at the end of the specification.

In the drawings:

Figure 1 is a front elevation of the upper portion of the punch press provided with a 40 guard or safety device constructed in accordance with and illustrating one embodiment of my invention;

Fig. 2 is a horizontal section taken substantially on the line 2—2 of Fig. 1;

Fig. 3 is a vertical section taken substantially on the line 3—3 of Fig. 2 with the parts in the position occupied when the guard is in the operative dotted line position of Fig. 1;

Fig. 4 is a side elevation of the entire press;

Fig. 5 is a detail view showing the devices for actuating the guard through the medium of the ram;

Fig. 6 is a section taken substantially on the line 6—6 of Fig. 5, and

Fig. 7 is a section similar to Fig. 6 but with the parts in another position.

Similar reference numerals throughout the several figures indicate the same parts.

The punch press in connection with which I have illustrated my invention comprises an upper frame 1 above a bed 2, the frame being provided with guides or ways 3 in which operate the slides 4 of a ram 5 having a journal block 6 connected to the crank 7 of the shaft 8 at the top of the frame so that the ram reciprocates back and forth toward and from the bed 2 upon each revolution of the shaft. 9 indicates a male die carried by the ram 5 and 10 a female die on the bed 2, 11 being the die clamps for the stationary die. The shaft 8 is driven by a drive wheel 12 through the medium of a clutch 13. The clutch is thrown in by a pull 75 on a rod 14 (Fig. 4) connected thereto at its upper end and connected at its lower end to a foot treadle 15 pivoted at 16 to the lower frame 17 of the machine which lower frame supports the upper frame 1 and bed 2. 80 Each depression of the treadle 15 and actuation of the clutch 13 joins up the drive wheel and shaft for one reciprocation of the ram 5, as will be understood, this being the usual general mode of operation of presses 85 of this kind.

In the practice of my present invention, I provide a bridge member 18 carried stationary by the frame 1 to span the ways 3 and the ram operating therein and at a preferably central point on the bridge is pivoted at 19 a guard arm 20 carrying a vane 21 the normal position of which and of the arm is shown in full lines in Fig. 1. Through mechanism hereinafter described, upon each 95 downward movement of the ram 5 toward the bed 2 the arm 20 is automatically swung to the right and with it the vane 21 to the dotted line position of Fig. 1 so that if the operator's arm or hand is in the dangerous 100 region between the two dies, it will be ejected laterally and thereafter the vane 21 will block access to this dangerous region.

A connection is provided between the guard arm 20 and the clutch controlling 105 mechanism 14—15 whereby the guard will be moved to its operative position upon each actuation of the treadle 15 for the purpose

of operating the clutch 13 and will reach that position in advance of the near approach of the ram to the bed 2 or of the dies carried, respectively, thereby. In the present instance, this connection comprises a pull rod or link 22 connected to the treadle 15 and to a bell crank lever 23 (Fig. 4) pivoted at 24 to the frame 1. The other arm of the bell crank is connected by a link 10 to a second bell crank 26 (Fig. 2) pivoted at 27 and provided with a socket 28 in its other arm. Slidably received within this socket 28 is the stem 29 of a block 30 pivotally connected at 31 to a link 32 that is 15 pivoted at 33 (Fig. 3) to an arm 34 on the hub 35 of the guard arm 20 or its shaft or pivot 19.

It will be seen from the above that each time the treadle 15 is depressed to throw in the clutch 13 the guard arm 20 will immediately be thrown in the operative position through the pull on the rod 22 and connected parts and thereafter and not until this has occurred will the ram 5 descend.

25 A latch 36 pivoted at 37 to the bridge member 18 is utilized to lock the guard in operative position so that releasing the treadle 15 before the ram has completed its movement will not cause the guard to withdraw just at the time it is needed. The latch is normally drawn to the right by a spring 38 so that a finger 39 thereon will engage above a locking shoulder 40 on a link 41 which, with a link 42, forms a toggle that 30 is straightened out when the pivot 19 of the guard is rocked to carry the latter to operative position as in Fig. 3. The link 41 is pivoted to the arm 34 at 43 and to the link 42 at 44 and the link 42 is in turn pivoted 35 at 45 to the bridge piece 18. A finger 46 on the latch 36 projects downwardly below the bridge to permit a manual release of the latch but in the normal working of the device, the latch is automatically tripped as the dies 9 and 10 come together (and the danger to the operator is past) by a cam shoulder 47 on a stop plate 48 fixed to the ram 5 to move therewith. This cam 47 comes in contact with the rearward boss 49 on the latch 40 36 and throws the latch downwardly and to the left so that the finger 39 disengages from the shoulder 40 on the toggle and allows the latter to move upwardly and the guard arm pivot 19 to revolve to the right again as the 45 guard arm takes up its inoperative position to the left. The guard arm is operated to and normally held in its inoperative position by a spring 50 (Fig. 4) that acts through the link 14 to raise the treadle 15.

50 As the treadle is raised it pushes upwardly on the link 22 and as previously described, this link is connected by a series of links and levers to the guard arm.

It is advisable to have a direct acting means for operating the guard arm by the

ram itself so that if the clutch 13 should stick, for instance, and cause the reciprocation of the ram to repeat upon a single depression of the treadle, the dangerous region between the dies would still surely be 70 rendered inaccessible to the operator's hand. To this end, a block 51 secured to the ram 5 is provided with a T slot or way 52 in which the stop plate 48 is adjustably held by a bolt 53. In this way is confined a stop 75 arm 54 (Figs. 6 and 7) that yields rearwardly on a pivot lug 55 that enters a recess in rear of plate 48 but is normally thrust forwardly by a leaf spring 56 in rear thereof. The upper end of the stop arm is 80 formed with a hook or shoulder 57 that is normally held by a spring in a position to engage within a groove 58 in the upper edge of the toggle link 42, as shown in Fig. 6. As the ram descends, this engagement takes 85 place at the proper time if the treadle connection, previously described, has failed to operate the guard arm 20 and the toggle is straightened out from the position of Fig. 5 to that of Fig. 3 which operates the guard 90 automatically into operative position before the ram can reach a point at which it would be dangerous for the operator's hands. The guard is operated by the engagement of the stop hook with the toggle in advance, of 95 course, of the tripping of the latch 36 by the cam 47 striking the boss 49. Both the cam 47 and the stop arm 54 being carried on the adjustable plate 48, they are adjusted in unison and the interval between their successive operations is maintained constant 100 throughout adjustments for differences in the throw of the ram 5.

On the return or upward movement of the ram, the cam stop 47 that has passed the 105 boss 49 in tripping the latch 36 rides over it again deflecting the latch idly and very slightly as the finger 39 rides against the under side of link 41, as shown in Fig. 5 and as soon as the toggle is released from the 110 latch on the down trip, the latch is held partially restrained toward the left in the figures. The contact of the stop shoulder 57 with the toggle is also a slip-off connection that causes only a momentary connection between the ram and guard arm. The groove 58 in the toggle is tapered off as shown in Fig. 7 so that as the toggle pivot 44 moves to the right in straightening, the stop or hook 57 will slide out of it and pass down in rear of the toggle as also shown in Fig. 7. The upper end of the stop finger 54 is beveled at 59 so that it can ride over the toggle on the upward movement of the ram, by yielding rearwardly against the spring 56 as it does so. 120

The operative position of the latch 36 is limited by a stop pin 60 fixed on the bridge 18 that limits its throw in this direction.

For the purpose of adjusting the mechanism of the press itself; adjusting the guard 130

actuating mechanism; adjusting the mechanism of the ram that coöperates with the guard actuating mechanism; disconnecting the guard mechanism entirely when required 5 as, for instance, in blanking, and in similar connections, I find it desirable to have the safety device displaceable as a unit and to this end the bridge piece 18 is connected to brackets 61 and 62 on the press frame 1 by 10 pins 63 and 64, one of which is removable to allow the bridge to pivot on the other and be swung laterally so that it is both itself rendered accessible with the mechanism mounted thereon and the parts of the 15 press in rear are also exposed. In the present instance, 63 is a pivot pin extending between ears on the brackets and 64 is a removable pin. The only constant connection between the guard actuating mechanism on 20 the bridge and the mechanism of the press is at the bell crank 26 but as before described, the stem 29 (Fig. 2) can be readily withdrawn in a forward direction from the socket 28 and this occurs automatically as 25 the bridge is swung forwardly while when it is moved back in place, the stem 29 can be readily reinserted. The other coöperating elements on the press and bridge respectively, as for instance, the stop arm 54 and 30 the toggle 41—42, realine themselves without special attention.

I claim as my invention:

1. In a safety device for punch presses, the combination with a press comprising a frame, a bed and a ram movable in the frame toward and from the bed, of a displaceable bridge mounted on the frame to span the ram, a movable guard carried by the bridge to block the interval between the bed and 35 ram, and mechanism also carried by the bridge for operating the guard, said mechanism being adapted to coöperate with the mechanism of the press when the bridge is in place to cause an actuation of the guard 40 with each actuation of the ram.
2. In a safety device for punch presses, the combination with a press comprising a frame, a bed, a ram movable in the frame toward and from the bed and controlling 45 mechanism for the ram, of a displaceable bridge pivotally mounted on the frame to span the ram, a movable guard carried by the bridge to block the interval between the bed and ram and mechanism also carried by 50 the bridge for operating the guard embodying a coupling member connecting said mechanism to the ram controlling mechanism when the bridge is in place to cause an actuation of the guard with each actuation 55 of the ram, said coupling member being adapted to detach itself as the bridge is swung out of position on its pivot.
3. In a safety device for punch presses, the combination with a press comprising a 60 frame, a bed, and a ram movable in the
- frame toward and from the bed, of a movable guard adapted to block the interval between the bed and ram, guard actuating devices comprising a toggle connected to the latter and to the frame, a device on the ram 65 adapted to coöperate with the toggle to operate the guard during the descent of the ram and a latch engaging with the toggle to lock the guard in operative position. 70
4. In a safety device for punch presses, the combination with a press comprising a frame, a bed, and a ram movable in the frame toward and from the bed, of a movable guard adapted to block the interval between the bed and ram, guard actuating 75 devices comprising a toggle connected to the latter and to the frame and a device on the ram having a slip-off engagement with the toggle to produce a momentary operation of the guard by the ram at a predetermined point in the travel of the latter. 80
5. In a safety device for punch presses, the combination with a press comprising a frame, a bed, and a ram movable in the frame toward and from the bed, of a movable guard adapted to block the interval between the bed and ram, guard actuating 85 devices comprising a toggle connected to the latter and to the frame, a device on the ram adapted to coöperate with the toggle to operate the guard during the descent of the ram, a latch engaging with the toggle to lock the guard in operative position, and a device on the ram arranged to trip the latch at a later point in the descent of the ram. 90
6. In a safety device for punch presses, the combination with a press comprising a frame, a bed, and a ram movable in the frame toward and from the bed, of a movable guard adapted to block the interval between the bed and ram, guard actuating 95 devices, a device on the ram having a slip-off engagement with the said guard actuating devices to operate and then clear the guard during the descent of the ram, a latch for locking the guard in operative position, and a device on the ram arranged to trip the latch at a later point in the descent of the ram. 100
7. In a punch press, the combination of a press having a frame and a ram reciprocating therein, said frame having uprights, one on each side of the ram, a bridge extending between said uprights, said bridge being hinged to one of the uprights and latched to the other upright, a guard mounted on said bridge to swing in a vertical plane in front of the ram, said bridge being capable of being released on one side and swung around carrying said guard therewith away from the ram. 115
8. In a punch press, the combination of a press having a frame and a ram reciprocating therein, said frame having uprights, one on each side of the ram, a bridge extending 120

1
between said uprights, said bridge being hinged to one of the uprights and latched to the other upright, a guard mounted on said bridge to swing in a vertical plane in front of the ram, said bridge being capable of being released on one side and swung around carrying said guard therewith away from

the ram, means for actuating said guard, said means detaching itself from the guard as the bridge is swung away from the ram. 10
